UNITED STATES PATENT OFFICE.

ACHILLO FABRIZIO, OF ELKTON, MARYLAND, ASSIGNOR OF ONE-HALF TO JOSEPH MARRA, OF ELKTON, MARYLAND.

TORPEDO.

Application filed March 14, 1925. Serial No. 15,470.

To all whom it may concern:

Be it known that I, ACHILLO FABRIZIO, a subject of the King of Italy, and residing at Elkton, in the county of Cecil and State of Maryland, have invented certain new and useful Improvements in Torpedoes, of which the following is a specification.

My invention relates to torpedoes and more particularly to the casing.

10 The object is to provide a light, inexpensive casing which, after being loaded with an explosive charge, may be quickly and efficiently sealed, and which will be of such strength as to produce a loud explosion.

15 This object, and other advantageous ends which will be described hereinafter, I attain in the following manner, reference being had to the accompanying drawing in which—

20 Figure 1 is a central section through a torpedo casing closed at one end,

Figure 2 a like view illustrating an explosive charge therein,

25 Figure 3 a like view illustrating both ends closed, and

Figure 4 a like view showing the casing closed and sealed.

Referring to the drawings, 1 indicates a short tube which may be cut from paper tubing, 2 disks closing the ends of the tube, 3 an explosive charge in the tube between the disks, and 4 flanges on tube 1 for securing the disks to the casing and formed by turning in the edges of tube 1. The flanges 30 are secured to the disks by a suitable adhesive filler 5.

In the process of manufacture, one end of the tube 1 is closed by turning in its edge to form flange 4 and then placing one of the 40 disks 2 on the flange. The tube is then filled with the explosive charge 3, after which it is closed by the second disk 2 as shown in Figure 2. The upper edge of the tube is then turned in to form a flange 4 to secure

this disk to the casing. The flanges 4 on 45 each end of the tube are then secured to the disks by the adhesive 5.

The torpedo above described may be made at low cost without danger of spilling the explosive charge in the handling, because 50 the disks temporarily hold the charge in the casing until they are firmly secured to the casing by flanges 4.

While I have described my invention as taking a particular form, it will be understood that the various parts may be changed without departing from the spirit thereof, and hence I do not limit myself to the precise construction set forth, but consider that I am at liberty to make such changes and 55 alterations as fairly come within the scope of the appended claims.

Having thus described my invention, what I claim as new and desire to secure by Letters Patent is:—

1. A torpedo casing consisting of an open ended tube; a disk within and closing each end of the tube; an explosive charge in the casing between the disks, and means filling the open ends of the tube for securing the 70 disks therein.

2. A torpedo casing consisting of an open ended tube; a disk within and closing each end of the tube; an explosive charge in the casing between the disks, and adhesive filling arranged in the open ends of the tube 75 for securing the disks therein.

3. A torpedo casing consisting of an open ended tube; a disk within and closing each end of the tube; an explosive charge in the 80 casing between the disks; flanges on the casing for securing the disks to the casing, and an adhesive filler for securing the flanges to the disks.

In testimony whereof I have signed my 85 name to this specification.

ACHILLO FABRIZIO.
